UNITED STATES PATENT OFFICE.

JOSEPH HENRI RIVET, OF WOONSOCKET, RHODE ISLAND.

TELEPHONE BRACKET OR SUPPORT.

Application filed April 20, 1920. Serial No. 375,323.

To all whom it may concern:

Be it known that I, JOSEPH HENRI RIVET, a citizen of the United States, residing at Woonsocket, in the county of Providence 5 and State of Rhode Island, have invented new and useful Improvements in Telephone Brackets or Supports, of which the following is a specification.

This invention relates to an improved and 10 novel bracket or support for what is commonly termed the "desk-telephone," and it is designed to be attached to the side wall of a desk, room, or other suitable and convenient fixture.

15 The main object of this invention is to provide simple, durable, economical, novel and efficient means for supporting the receiver of the instrument, intended for use during a time when it is necessary to leave 20 the telephone temporarily, before the conversation has been completed, or while waiting the arrival of the desired party when some other person has answered the signal and for various other reasons.

25 Further objects of the invention are to provide improved supporting means whereby the instrument can be quickly and easily removed from the support and used in the ordinary manner; to provide additional 30 convenient means for supporting the receiver when it is necessary to call another person to the phone or to leave it for a few moments and to furnish means connected thereto for supporting the telephone directory.

35 The foregoing and such other objects as may appear from the ensuing description are attained by the construction, combination, arrangement and location of the parts hereinafter more fully described, illustrated 40 by the accompanying drawings, and particularly pointed out in the claim appended hereto, it being understood that slight changes in the precise form, proportions and minor details of the construction may 45 be resorted to without departing from the spirit of the invention or sacrificing any of its advantages.

In the accompanying drawings forming a part of this specification it will be seen that:

50 Figure 1, is a side elevation of the device embodying the invention, showing one of the supports partly in section, and

Figure 2, is a front elevation.

55 Figure 3, illustrates one modified form of securing the forks to the wall 2.

Figure 4, is a front elevation of Figure 3.

Figure 5 is a top plan view showing still another form of construction of the lower fork intermediate the upper fork and the shelf.

Figure 6 illustrates another modified construction, while

Figures 7 and 8 illustrate still other modified forms.

Similar numerals of reference are employed to designate like parts throughout Figures 1 and 2 of the drawings.

In carrying out this invention, as illustrated, it will be seen that 1, indicates the bracket members, which are fixedly secured 70 in any suitable or desirable manner to the wall or other stationary support 2, and connected to each of said brackets in a stationary manner is one end of a rod 3. Adjustably secured upon this rod 3 are an upper outwardly extending fork 4, a lower outwardly extended shelf 5, and a lower outwardly extended fork 6. The peripheral edge of the shelf 5 is provided with an upward extension forming a rim 7, (as shown in section 75 in Fig. 1) the purpose of which is to prevent the base of the telephone 8 from slipping off the shelf and thus permitting the instrument to fall. A collar 9 is secured in any suitable manner around the column of 80 the instrument to assist in holding it between the arms of the upper fork 4, which collar is not essential and may be dispensed with if desired.

It will be perceived that the upper and 90 lower extended forks 4 and 6, as well as the shelf 5, are adjustably secured to the rod 3, by means of the screws 10, so that the position of these members may be changed and shifted on said rod as desired, and the rod 95 may be so mounted and connected to the brackets 1 as to allow these parts to be swung from left to right, carrying the phone, which provides a great convenience under certain conditions.

100 Secured to the lowermost extending fork 6, in any suitable manner is a depending hook member 11, adapted to support a telephone directory at a convenient location, although if desired, said member 11 may be secured to the device at any point desired.

105 It will be seen that the device thus described permits a support for a phone and use of said phone in the ordinary well known manner. However, when occasion demands a party to leave the phone during a telephone conversation, for instance to call 110

a second party or to obtain a pencil or the like, the receiver may be placed on the hook 6, where it will be in ready access upon return of the first or second party to the 5 phone. Manifestly the position of the auxiliary hook 6 is that shown in order to remove the liability of a person placing the receiver on hook 6 after a conversation is completed instead of the hook of the telephone.

Experience has demonstrated that it is not always preferable to have the forks and shelf and their appurtenances secured to the rod 3, and hence I have devised the modified 15 constructions that appear in the drawings and referring to which:

In Figures 3 and 4, the fork 4' may be secured to the wall 2 direct and hence elimination of the rod 3 is brought about. Of course it is to be understood that the fork 20 4' is used in lieu of the fork 6, also and that when said fork 4' is employed it is secured to the wall 2 by the integral portion 20.

As appears in Figure 5, the shelf 7' is 25 secured directly to the wall 2 and in such case the fork 6' may be connected to the bracket 31 in a swinging manner by means of the rod 30.

In Figure 6, the shelf 7' is illustrated as 30 connected directly to the wall by means of the member 21 and said shelf has a fork 6'' formed integral on its peripheral edge.

In Figure 7 the shelf 7' rests on the arm 23 which in turn is secured directly to the 35 wall by member 22. As appears in the drawing, the shelf is provided at its underside with a downwardly reaching arm 24 that extends forwardly and terminates in a hook 25.

In Figure 8, I illustrate still another form 40 of bracket in which the forks 4'' and arm

29 are formed integral with the arm 40 that is secured directly to a supporting member.

It will be apparent that in the modified forms of the device, the same is very inexpensive to produce and contains the minimum amount of parts and hence is in some instance preferable to the device shown in Figures 1 and 2.

Having described my invention, what I claim and desire to secure by Letters Patent is:—

In a telephone support the combination of wall brackets adapted to be secured to a wall in a removable manner and having apertures in their free ends, a rod adapted to seat in the apertures and to be turned with respect to the brackets, an arm adjustably secured to the rod near the upper end thereof and to turn therewith and having an outer forked portion adapted to receive and grip the staff of a telephone, an arm arranged at a point on the rod slightly below the transverse center thereof and adjustably secured thereto and adapted to turn with the rod, a tray mounted on the last named arm, an arm mounted beneath the second arm on the rod and adjustably secured thereto and movable therewith and having a forked free end adapted at times to receive a telephone receiver, and a hook formed integral on the last named arm to receive a telephone directory.

In testimony whereof I have hereunto set my hand in presence of two subscribing witnesses.

JOSEPH HENRI RIVET.
